CLAIM

The ornamental design for a vehicle article carrier clamping support, as shown and described.

DESCRIPTION

FIG. 1 is a perspective view of a vehicle article carrier clamping support showing my new design;

FIG. 2 is an exploded perspective view thereof;

FIG. 3 is a side elevational view thereof, the opposite side being a mirror image of that shown;

FIG. 4 is a top plan view thereof;

FIG. 5 is a front elevational view thereof;

FIG. 6 is a bottom plan view thereof;

FIG. 7 is a rear elevational view thereof; and

FIG. 8 is a sectional view thereof taken along line 8—8 in FIG. 4.

FIG. 1

FIG. 2

FIG. 3

FIG. 4

FIG. 5

FIG. 6

FIG. 7

FIG. 8
